Primary Examiner—Doris V. Coles
Attorney, Agent, or Firm—Richard C. Litman[57] **CLAIM**

The ornamental design for a fish bite detector, as shown and described.

DESCRIPTION

FIG. 1 is a perspective view of a fish bite detector showing my new design;

FIG. 2 is a front elevational view thereof;

FIG. 3 is a right side elevational view thereof;

FIG. 4 is a rear elevational view thereof;

FIG. 5 is a top view thereof;

FIG. 6 is a left side elevational view thereof; and,

FIG. 7 is a bottom view thereof.

The broken line showing of environment in FIG. 1 is for illustrative purposes only and forms no part of the claimed design.
